(57) **CLAIM**

The ornamental design for an automobile floor mat, as shown and described.

DESCRIPTION

FIG. 1 is a top view of an automobile floor mat of the present invention.

FIG. 2 is an exploded view thereof; and,

FIG. 3 is a sectional view of thereof along line 3—3.

The shading that can be seen on the center square of the automobile floor mat is used to represent a wood surface.

The crisscross pattern on the front surface of the automobile floor mat is understood to be distributed uniformly over the surface on which it is only intermittently shown and represents a texture of material.
